UNITED STATES PATENT OFFICE.

FRANK C. SINGLETON, OF CHICAGO, ILLINOIS, ASSIGNOR TO STANDARD OIL COMPANY,
OF WHITING, INDIANA, A CORPORATION OF INDIANA.

STATIC-ELECTRICITY-GROUNDING DEVICE.

Application filed March 27, 1924. Serial No. 702,297.

To all whom it may concern:

Be it known that I, FRANK C. SINGLETON, a citizen of the United State, residing at Chicago, in the county of Cook and State of Illinois, have invented a new and useful Improvement in Static-Electricity-Grounding Devices, of which the following is a specification.

My invention relates to an improvement 10 in the class of devices used for grounding static electricity generated in bodies, such as vehicles, bedsteads, and printing presses which are electrically insulated from the ground by rubber tires, insulating casters, 15 and the like, to prevent undesirable effects on the occupants or other objects in such bodies, from the electricity.

I have more immediately devised my device for protecting rubber-tired truck-tanks 20 used for transporting volatile inflammable liquids against hazard from static electric sparks, while being filled through pipe-lines from storage-tanks, whereby static electricity is generated, presumably by friction 25 of the liquid in coursing through the pipe-lines, and is liable to cause explosion in the truck-tanks.

My device for the aforesaid purpose is 30 illustrated in the accompanying drawing, in which—

Figure 1 is a plan view of the separably attachable handle-equipped head of the device through which the flexible grounding wire, shown broken away, extends from the 35 metal attaching clip on its advance-end;

Figure 2 is a section on line 2—2, Fig. 1;

Figure 3 is an enlarged broken and partly sectional view showing the head illustrated in the preceding figures in electrical contact-engagement with the companion-member 40 on the object to be protected;

Figure 4 is an enlarged end view of the aforesaid companion-member; and

Figure 5 is a broken and partly sectional 45 view in elevation representing the two members coupled together in operative position.

At A is represented a portion of the shell 50 of an ordinary truck-tank, such as is in common use for transporting volatile inflammable liquids, such as gasoline, to filling stations, and will be understood to be carried on rubber-tired wheels and thus electrically insulated from the ground.

A metal contact-ball 6 having a neck 7 55 extending from a base 8 and forming one of the two members of my grounding device, is permanently secured, as by riveting through its base, to the shell A to project therefrom in desirably accessible position. 60

The other member comprises a head 9, shown of general rectangular shape and preferably formed entire of insulating material, such as wood, with a tubular wooden handle 9^a extending from one end and a resilient 65 metal clip 10 secured to extend from its opposite end, the clip-jaws being provided with series of perforations 10^a near their advance-edges, forming pairs, the opposite members of which should aline with each other. A 70 binding-post 11 projects centrally from the base of the metal clip into a socket 12 in the adjacent end of the head 9, from which socket a bore 13 extends through the head and the handle to a socket 14 formed in the 75 end of the latter and in which are confined the end-coils of a helical wire-shielding spring 15 having the coils of its outer end confined about the stem of a hollow tip 16, preferably of insulating material, such as 80 hard rubber. An insulated conducting-wire 17 extends from the binding-post 11 through the bore 13 to a desired length beyond the handle 9^a, for attachment, as at a binding-post 11^a to an electricity-grounding medium 18, which may be the pipe-line 85 through which the tank A is to be filled from a storage-tank (not shown), a post, or other suitable grounding medium.

The clip and conductor-carrying head remain constantly in position for use, as indicated in Fig. 5, whereby when a tank wagon provided with a contact-ball 6 is in place to be filled from the storage, it will be the duty of the person attending to the filling operation, before starting it, to apply the clip 10 to the ball 6 to grip the latter between the resilient clip-jaws and into engagement with any of two opposite perforations 10^a in the series thereof. This engagement insures 95 retention of the parts 6 and 10 in good electrical contact and is produced between any pair of the opposite perforations 10^a which the operator may hurriedly happen to strike in applying the spring-clip to the contact-ball. 100

The coil 15 affords a flexible shield to the insulation-covered conductor, and with the 105

tip 16 serves to protect the insulation against injury from sharp bends, and the like, in handling the head-member 9.

By observing the precaution of applying the clip on the member 9 to the ball 6 on any truck-tank A preparatory to filling it in the manner described, my device will reliably ground any static electricity or static electric charge tending to accumulate in the tank A; or serve to equalize difference in static potential which might otherwise tend to build up between the tank, while undergoing filling, and the fill-pipe, whereby such static charge, or difference of potential will not become great enough to cause a spark to jump between the truck-tank and fill-pipe to produce the hazardous condition referred to.

I realize that considerable variation is possible in the details of construction herein shown and described, and I do not intend to limit my invention thereto except as point-

ed out in the appended claim, in which it is my intention to claim all the novelty inherent in my invention as broadly as permissible by the state of the art.

25

I claim—

A static electricity grounding device comprising, in combination, a contact-ball adapted to be secured to an insulated body to be protected, an insulating head carrying a metallic spring clip having jaws provided with a series of pairs of oppositely disposed perforations to grip said ball, said head being of a length to extend a relatively material distance laterally beyond the contact-ball when the same is engaged by any one of said pairs of perforations, whereby said parts may be caused to engage at any one of said pairs of jaw perforations without predetermined alinement, and a conductor connected to said clip.

FRANK C. SINGLETON.
